UNITED STATES PATENT OFFICE.

CLARENCE W. COURT, OF CHICAGO, ILLINOIS, ASSIGNOR TO WALTER P. MURPHY, OF CHICAGO, ILLINOIS.

DROP-END GONDOLA CAR.

1,268,547.

Specification of Letters Patent. Patented June 4, 1918.

Application filed August 1, 1917. Serial No. 183,877.

To all whom it may concern:

Be it known that I, CLARENCE W. COURT, a citizen of the United States, residing at Chicago, in the county of Cook and State 5 of Illinois, have invented certain new and useful Improvements in Drop-End Gondola Cars, of which the following is a specification.

My invention relates to drop end gondola 10 cars and has as its primary object to provide a new and improved drop end or gate for the above type of car, which will resist the stresses due to the cargo thrusts against the end more effectively than the end gates now 15 in use.

Drop end gondola cars are provided with drop end gates so as to permit the carrying of structures longer than the car, such for example, as steel girders or railroad rails, 20 as well as bulk freight. When carrying cargoes such as girders or rails the end gates lie flat on the floor and must, therefore, be strong enough to support the weight of the cargo. It is customary to provide the end 25 gate of a car of this type with flexible or link hinges, this type of hinge being preferred so that the gate may be readily folded down upon the floor of the car. The hinges ordinarily do not take any of the stresses of the 30 cargo against the gate. Abutments are ordinarily provided for this purpose on the side walls and floor of the car. If the pressure of the cargo against the end gate is considerable, as it is likely to be, there is a tendency 35 for the gate to bulge. This is undesirable in itself as the structure of the gate is weakened and it is likely to be given a permanent set which makes it inconvenient to manipulate. Moreover, any considerable outward 40 bulge of the gate tends to draw up the lower edge of the gate at the middle causing a gap between the gate and the floor abutment through which bulk material can leak. The primary object of my invention is to provide 45 the end gate of a drop end gondola car with a hinge or hinges so constructed and arranged as to take some of the stresses on the gate with the purpose particularly of preventing the bulging of the gate and the consequent tendency of the car to leak as above 50 set forth. My invention contemplates more particularly the provision of a suitable hinged connection between the car frame and the end gate put under tension by pressure on the gate, whereby certain stresses in-

incident to the cargo thrust against the end gate, more particularly the stresses against the bottom of the gate, will be transmitted directly through the hinges employed in such connection to the under framing of the car. 60

The invention consists in the novel arrangement, construction and combination of parts for carrying out the above stated object and such other objects as may appear from the following description. 65

The invention is illustrated in the accompanying drawing in which like characters of reference designate corresponding parts and in which—

Figure 1 is an end view of a drop end 70 gondola car constructed in accordance with my invention.

Fig. 2 is a vertical sectional view taken on line 2—2 of Fig. 1.

Fig. 3 is a plan section taken on line 3—3 75 of Fig. 1 with certain parts removed for the purpose of clearness in illustrating the hinged connection between the end gate and the under framing of the car.

Fig. 4 is a vertical sectional view, similar 80 to Fig. 2, illustrating a modified form of the invention.

Referring to the drawings, and particularly to Figs. 1 to 3 inclusive, 10, 10 designate the side walls of the car, 11 the flooring, 12 the end sill, and 13, 13 and 14, 14 the center and side sills, respectively, of the under framing of the car. The flooring may be secured to the under framing of the car in any suitable manner, as, for example, by 85 means of the nailing strips 15, which extend longitudinally of the car and which may be bolted or otherwise secured to the upper flange of the center and side sills. Angular members 16 and 17 are bolted to 90 the inner and outer surface of the vertical edges of the side walls and provide abutments 18, 18 for the vertical edges of the end gate. An angular strip 19 extends transversely of the car and is secured to the 95 under framing so as to provide an abutment for the lower edge of the gate when the gate is raised to its upstanding position. The drop end gate illustrated in Figs. 1 to 3 inclusive consists of a metal sheet 20 formed 100 with pressed strengthening and rigidifying corrugations 21 extending horizontally across the end gate and which forms a sinuous structure in cross-section. The corrugations in this construction are shown as 110

being pressed outwardly from the plane of the sheet and terminating within the edges thereof so as to provide flat marginal portions adapted to bear against the vertical abutments 18, 18. The upper and vertical margins of the sheet 20 are bent at right angles to the plane of the sheet in a manner to provide flanges 22, 23 and 24 along the upper and vertical edges thereof. These flanges 10 form a rigidifying rim and make a very strong and durable structure for supporting the weight of the cargo when the gate is in the position shown in the dotted lines of Fig. 2, and also provide the reinforcement necessary in resisting the cargo thrusts 15 against the end when the same is in its upright position. The upper flange 22 is further reinforced by means of the angle 25. In drop end gondola cars it is desirable to 20 reinforce the end as much as possible transversely of the car so as to transmit the strains due to the cargo thrusts to the side walls of the car. This manner of construction also minimizes the danger of the end 25 gate buckling or being otherwise distorted under the weight of the cargo when the gate is lowered to the dotted line position in Fig. 2. With a view of providing satisfactory reinforcement for car ends of this type, I 30 preferably provide the end with a reinforcing angular strip 26 secured to the sheet 20 along the lower edge thereof and adapted to abut against the angular strip 19 when the gate is raised to its upstanding position. 35 Designates a wooden lining for the end which is secured to the inner surface of the sheet 20 by means of nailing strips 28. These strips are preferably fitted into certain of the corrugations and are secured 40 therein by means of bolts 29 which extend through said lining and nailing strips. Metal strips 30 prevent the heads of the bolts from becoming embedded in the wooden lining 27. The lining arrangements 45 just described are not claimed herein as they are claimed in a divisional application filed April 24, 1918, Serial No. 230,396. The end gate is preferably connected to the under framing of the car by means of flexible or 50 link hinges. It should be understood that any number of these hinges may be used that may be found desirable to hold the end gate in proper position with respect to the abutments 18-19. In the drawing I have 55 shown two such hinges, each of which consists of a U-bolt 31 riveted to the horizontal flange of the angle 26 at the lower edge of the gate, a staple 32 secured to one of the center sills of the under framing, and a link 33 connecting said U-bolt and staple. The link is preferably given a twist so that its opposite ends stand at substantially right angles to each other. The flooring 11 is cut away as at 34 to permit the upper portion 60 35 of the link to extend through the flooring

in a manner to permit the link to move freely. The angle 26 is also cut away, as indicated at 36, Figs. 2 and 3, to provide the necessary clearance for the loop 35 of the link 33. 70

The staple 32 is secured to the center sills a short distance back of the U-bolt 31, so that the connecting link 33 will be held taut in an angular position when the gate is in its upstanding position. The lower edge of the car is thereby held down in proper position so that the gate cannot bulge and gap at the middle. 38-38 designates latch members for holding the end gate in its upstanding position against the above mentioned abutments. 75

Referring to Fig. 4: In this figure I have illustrated a modified form of my invention. The end gate illustrated in this figure consists of a sheet metal panel 20^a provided with inwardly pressed corrugations 21^a. The vertical edges of said panel are bent at right angles to the plane of the sheet so as to provide reinforcing angular members 23^a-24^a substantially the same as those shown at 23 and 24 in Figs. 2 and 3. The upper and lower margins of the end panel shown in this construction are reinforced by a bulb angle bar 28 and a channel member 39 respectively. The hinged connection 95 illustrated in this figure consists of U-bolt 40 secured to the channel member 39 at the lower edge of the gate, a staple 41 riveted to the under framing of the car a short distance back of the U-bolt 40 in substantially 100 the same manner as illustrated in connection with Figs. 1 to 3 inclusive, and a link 42 connecting the said U-bolt and staple. The abutment in this construction consists of an angular member 43 which is arranged 105 so that its vertical flange extends along the lower edge of the gate so as to provide an abutment substantially the same as that shown in the other figures. This angular member is also secured to the end sill 12^a by 110 means of the rivets 44 and is further rigidified by cross-members 45. This modified construction in other respects may be substantially the same as the structure illustrated in the other figures and need not be 115 described herein. 120

While I have illustrated my invention in certain preferred embodiments, it is obvious that further modifications in the structure might be made without departure from the spirit of my invention. I therefore wish it to be understood that I do not limit myself to the exact structure shown and described, except so far as specific limitations may appear in the appended claims. The modification shown in Fig. 4 is not claimed specifically herein, being the subject matter of the divisional application above mentioned. 125

I claim:

1. In a drop end gondola car, the com- 130

- bination with the under frame of the car, of a drop end gate, and means for flexibly connecting said gate to the under frame at points inwardly and below the lower edge 5 of the gate whereby the lower edge of the gate is held down against the tendency of the gate to bulge.
2. In a drop end gondola car, the combination with the longitudinal sills of the car, of a drop end gate, and means for flexibly connecting said gate directly to said longitudinal sills.
3. In a drop end gondola car, the combination with the under-framing of the car, of a drop end gate for the car, and means for flexibly connecting said gate to the said under-framing, comprising a link secured to the gate and to the under-framing so as to transmit stresses, due to cargo thrusts 15 against the gate, to said under-framing.
4. In a drop end gondola car, the combination with the under-framing of the car, of a drop end gate for the car, and means for flexibly connecting said gate to the said under-framing, comprising a link secured to the lower edge of the gate and to the under-framing so as to transmit stresses, due to cargo thrust against the gate, to said under-framing.
5. In a drop end gondola car, the combination with the under-framing of the car, of a drop end gate for the car, and means for flexibly connecting said gate to the said under-framing, comprising a link secured to the gate near the vertical center of the end, and to the under-framing so as to transmit stresses, due to cargo thrusts 20 against the gate, to said under-framing.
6. In a drop end gondola car, the combination with the side walls and under-framing of the car, of a drop end gate for the car, abutments for said gate secured to the side walls, an abutment for the lower edge of said gate, and means for hingedly connecting said gate to the under-framing, comprising a link flexibly connected to the lower edge of said gate and to said under-framing and adapted to transmit stresses, due to the thrusts of the cargo against the 25 end, to the said under-framing.
7. In a drop end gondola car, the combination with the side walls and under-framing of the car, of a drop end gate for the car, abutments for said gate secured to the side walls, an abutment for the lower edge of said gate, comprising an angular member extending transversely of the car, and means for hingedly connecting said gate to the under-framing comprising a link 30 flexibly connected to the lower edge of said gate and to said under-framing and adapted to transmit stresses, due to the thrusts of the cargo against the end, to the said under-framing.
8. In a drop end gondola car, the combination with the side walls and under-framing of the car, of a drop end gate for the car, abutments for the vertical edges of said gate secured to the side walls, an abutment for the lower edge of the gate extending 35 transversely of the car and secured to the under-frame, and means for hingedly connecting said gate to the under-frame, comprising links having their ends twisted at substantially right angles to each other and flexibly secured to the lower edge of said gate and to the said under-frame so as to be put under tension by the cargo thrusts against said gate.
9. In a drop end gondola car, the combination with the side walls and center sills of the car, of a drop end gate for the car, abutments for the vertical edges of said gate secured to the side walls, an abutment for the lower edge of the gate extending 40 transversely of the car and secured to the under-frame, and means for hingedly connecting said gate to the center sills, comprising links having their ends twisted at substantially right angles to each other and flexibly secured to the lower edge of said gate and to the said center sills so as to be put under tension by the cargo thrusts against said gate.
10. In a drop end gondola car, the combination with the side walls and under-framing of the car, of an end gate for said car comprising a sheet metal panel formed with outwardly pressed corrugations and having its top and vertical edges bent at 45 right angles to the main portion of the panel to provide rigidifying marginal flanges, an angle secured to the top marginal flange, an angle secured to the lower edge of said sheet, an abutment for the lower edge of the gate, abutments for the vertical edges of the gate, and means for hinging the said gate to the under-framing of the car, comprising a U-bolt secured to the lower edge of the door, a staple secured to the under-framing of the car a short distance back of said U-bolt, and a twisted link connecting said U-bolt and staple. 50
11. In a drop end gondola car, the combination with the body of the car, of an end gate, means on the body of the car providing abutments for the edges of the end gate when the latter is in closed position, and means connecting the gate to the body of the car comprising a hinged-forming member engaged with the lower edge of the gate and engaged with the body of the car at a point inwardly of the lower edge of the gate, which hinge member is put in tension when the gate is under pressure of the cargo. 55
12. In a drop end gondola car, the combination with the body of the car, of an end gate, means on the body of the car providing abutments for the edges of the end gate. 60

- gate when the latter is in closed position, and means connecting the gate to the body of the car comprising a hinge-forming member engaged with the lower edge of the gate 5 and engaged with the body of the car at a point inwardly of and below the lower edge of the gate, which hinge member is put in tension when the gate is under pressure of the cargo.
- 10 13. In a drop end gondola car, the combination with the body of the car, of an end gate, means on the car body providing abutments for the edges of the end gate when the latter is in closed position, and means 15 for hinging the gate to the car comprising a member flexibly connected with the lower edge of the gate and flexibly connected with

the car body and disposed so as to transmit cargo thrust on the inside of the gate to the car body.

20

14. In a drop end gondola car, the combination with the body of the car, of an end gate, means on the car body providing abutments for the edges of the end gate when the latter is in closed position, and means 25 for hinging the gate to the car comprising a member flexibly connected with the lower edge of the gate and flexibly connected with the car body and disposed so as to constitute means for holding down the lower edge of 30 the gate against the tendency of the gate to bulge and gap at the bottom.
